UNITED STATES PATENT OFFICE.

JOSEPH SHAW GAUNT AND HARRY DYSON, OF MANCHESTER, ENGLAND.

YARN-GUIDE EYE.

1,257,213.

Specification of Letters Patent. Patented Feb. 19, 1918.

Application filed June 18, 1917. Serial No. 175,260.

To all whom it may concern:

Be it known that we, JOSEPH SHAW GAUNT and HARRY DYSON, of Manchester, in the county of Lancaster, England, have invented 5 certain new and useful Improvements in Yarn-Guide Eyes, of which the following is a specification.

The object of the invention is to simplify the method of carrying and retaining the 10 yarn guide eye upon the cup or flier so that it may be easily and quickly removed when worn by the friction of the yarn as it passes through the eye and a new eye quickly and firmly substituted.

15 The yarn guide may include a yarn-receiving eye, a shank, and a shank base formed to slide in a suitable groove formed in the top face, or other convenient position in the flier. The groove is made of 20 sufficient depth to permit the shank base to be completely embedded therein to a sufficient depth to allow a bridge to be engaged with the flier above the shank base, so that to locate the guide in position it may 25 be necessary to slide the base below the bridge.

The guide is so made that the base enters below the bridge in a direction opposite to the direction of revolution. These 30 details will now be more precisely described with reference to the accompanying sheet of drawings in which—

Figure 1 is a plan of the upper face of the cup or flier.

35 Fig. 2 is an elevation partly in section.

Fig. 3 is a view similar to a portion of Fig. 2 showing a special form of yarn guide with a two-part base and stem.

An annular groove A is formed in the 40 upper or other surface of the cup or flier B and of sufficient depth to allow the introduction of a bridge extending across the groove above its bottom, said bridge being preferably composed of two or more pins

45 C, D, adapted to coöperate with the yarn guide and groove. Said guide as shown by Fig. 2 includes an eye E, a shank E' and a shank base E² formed to enter the groove A, the said base being adapted to be inserted 50 by sliding it in the groove below the bridge. The forward rotation of the cup or flier maintains the bridge portion formed by the pin C in contact with the shank E' and prevents the base from sliding out from below

55 the bridge and always tends to retain it in the position shown and prevent it from

flying out, this tendency being aided by the drag of the yarn. Any suitable form of eye may be employed, either integral with or firmly attached to a suitable shank. For 60 soft yarn an eye E³ having a double hook or loop formation such as shown in Fig. 3 may be used, so that the yarn may be given one or more turns around the eye in order to take up the strain on the yarn from between the front roller and the cup or flier and transfer the strain to the winding point where it is fully twisted and more able to 65 withstand the strain of winding and overcome the friction of the spindle which with 70 its bobbin or the like is rotated by the pull of the yarn when in operation.

In order to better support the eye E³ in position, the shank may be composed of two members E⁴, E⁵, and the shank base 75 of two members E⁶, E⁷ projecting in opposite directions from the shank, one of the base members being shorter than the other. The longer base member is first inserted below the pin D and pushed under the same 80 until the outer end of the shorter member passes the other pin C, when the shorter member will enter the groove between the pins. The shorter member may now be pushed under the pin C until arrested by 85 contact of the shank with said pin, which will happen before the outer end of the longer member passes from under the pin D.

Claims:

1. A rotary cup or flier having a groove, 90 a bridge in said groove, and a removable yarn guide including an eye, a shank and a shank base, slidable in the groove, the shank and base being formed to coöperate with said groove and bridge in retaining 95 the guide in place on the flier, the shank being arranged to abut against said bridge to limit the sliding movement in one direction.

2. A rotary cup or flier having a groove, 100 spaced apart pins bridging the groove, and a removable yarn guide including an eye, a shank and a shank base, said base being slidable in the groove under said pins, and said shank being arranged to abut against 105 one of said pins to limit the sliding movement in one direction.

3. A rotary cup or flier having a groove, 110 spaced apart pins bridging the groove, and a removable yarn guide including an eye, a shank and a shank base, said base being composed of longer and shorter members

projecting in opposite directions from the shank and slidable in the groove, said pins being spaced apart to permit the insertion of the shorter base member between them after the longer base member has been engaged with one pin, and to also permit a subsequent sliding movement of the base to engage the shorter member and the shank with the other pin, the shank being arranged to abut against one of said pins to

limit the sliding movement in one direction.

In testimony whereof we have affixed our signatures in presence of two witnesses.

JOSEPH SHAW GAUNT.
HARRY DYSON.

Witnesses to signature of J. S. G.:

J. W. NASMITH,
A. HAMILTON.
